[57] CLAIM

The ornamental design for a buoyancy compensator
with an adjustable strap, as shown and described.

DESCRIPTION

FIG. 1 is a front perspective view of a buoyancy compensator with an adjustable strap showing my new design;

FIG. 2 is a reduced front elevational view thereof;

FIG. 3 is a reduced right side elevational view thereof;

FIG. 4 is a reduced rear elevational view thereof;

FIG. 5 is a reduced top plan view thereof;

FIG. 6 is a reduced bottom plan view thereof; and

FIG. 7 is a rear perspective view thereof.

The broken lines shown in all views of the drawing are
for illustrative purposes only and form no part of the
claimed design.

FIG. 1

FIG. 2

FIG. 3

FIG. 4

FIG. 5

FIG. 6
